UNITED STATES PATENT OFFICE

FREDERICK SCHWEIGERT, OF NEW YORK, N. Y.

WRENCH

Application filed January 18, 1930. Serial No. 421,642.

This invention relates to new and useful improvements in a wrench.

The invention has for an object the provision of a device of the class mentioned which is of simple durable construction, dependable in use and efficient in action, and which can be manufactured and sold at a reasonable cost.

The invention proposes a head member 10 with stationary and adjustable jaws having replaceable jaw plates and pivotally connected with a handle, and means for holding said head member in adjusted angular positions on its pivotal axis. The invention also proposes a means for disengaging said holding means in the closed position of said jaws.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a wrench constructed according to this invention.

Fig. 2 is a vertical sectional view taken on the line 2—2 of Fig. 1.

Fig. 3 is a vertical sectional view taken on the line 3—3 of Fig. 1.

Fig. 4 is a horizontal sectional view taken on the line 4—4 of Fig. 3.

Fig. 5 is a view similar to a portion of Fig. 1 but illustrating another embodiment.

Fig. 6 is a vertical sectional view taken on the line 6—6 of Fig. 5.

Fig. 7 illustrates various tongue constructions for use in lieu of the construction shown in Fig. 6.

Fig. 8 is another view similar to a portion of Fig. 1, but illustrating a modification.

Fig. 9. is a fragmentary plan view of Fig. 8.

Fig. 10 is a side elevational view of a wrench of modified form constructed according to this invention.

The wrench consists of a head member 12 with a stationary jaw 13 and a movable jaw 14, both having replaceable jaw plates 15,

and pivotally connected with a handle 16, and means for holding said head member in adjusted angular positions on its axis.

The movable jaw 14 has a slide portion 17 engaged thru an opening in the stationary jaw. The slide portion has longitudinal side ribs 18 engaging in corresponding grooves in the stationary jaw. Teeth 19 are formed upon one of the sides of said slide portion 17 and mesh with a worm 20 rotatively mounted in the stationary jaw and reachable from the sides of the jaw due to an opening 21 formed in the latter element. The jaw plates 15 are formed with tongue portions 22 engaging in grooves in the jaw, and a pin 23 engages thru the jaw and the tongues for holding the jaw plate in positions.

The head member 12 has a lug 24 engaging between a pair of lugs 25 formed on the handle 16. A tubular member 26 is fixed in the said central lug 24 and engages in apertures in the lugs 25 so as to constitute the said pivotal action. The handle 16 may be held stationary and the head member 12 pivoted in a horizontal plane any amount to one side or the other.

The means for holding the said head member in adjusted angular positions on its pivotal axis consists of teeth 27 projecting from one of the ends of the tubular member 26 and encircled by teeth 28 projecting from the outer side of one of the lugs 25. A stem 29 extends into the tubular member 26 and at its inner end is provided with a head 30, while at its outer end is provided with a disc 31 having a pair of diametrically opposite teeth 32 engageable between the space of the teeth 27 and 28 as shown in Fig. 4 to hold the lug 24 in a rotative latched position relative to the lugs 25. A spring 33 acts between the head 30 and the tubular member 26 for normally urging the stem 29 so that the teeth 32 engage between the teeth 27, 28. In the adjusting operation, the disc 31 is first manually raised from the tubular member 26 so as to permit manual adjustment of the head member 12 relative to the handle 16. When a desired position is reached, the disc 31 is released and its teeth 32 again interengage the teeth 27 of the tubular member.

In the modified form of the device illustrated in Fig. 6, the wrench is shown provided with jaw plates 15' differing from the jaw plates 15 in that they are provided with outer teeth 34 and facing flanges 35. The flanges 35 are arranged flush against the sides of the jaw and the pins 23 extend thru the flanges and the tongues 22 for accomplishing the securing in place. In other respects the device is similar to the one just described. In Fig. 7 several different forms of tongues have been shown for use in lieu of the tongues 22 of the jaw plates. Numeral 36 indicates a dovetailed tongue, 37 a T shaped tongue and 38 a bead tongue.

In the modified form of the device illustrated in Figs. 8 and 9, a means has been shown for disengaging said holding means in the closed position of the jaw. It consists of a flange 39 arranged upon the periphery of the disc 31. A finger 40 engages upon the top of the flange 39 and extends into a recess 41 formed in the stationary jaw. At its inner end 42 this finger is pivotally mounted. A spring 43 acts between the stationary jaw and the finger for normally urging it down against the flange so as to restrain upward motion of the disc 31.

This restraining action of the spring prohibits the lifting of the finger 40 and subsequent angular adjustment of the head member relative to the handle. A pin 44 projects from one of the ribs 18 of the slide 17 and in the completely closed position of the jaw engages against the bottom of the finger 40 to raise the finger off on the flange 39 so as to permit the raising of the disc. The worm 20 may be rotated for moving the jaws to the closed position and the pin 44 to raise the finger.

In the modified form of the device illustrated in Fig. 10, a handle 16' has been illustrated connected at each end with a head member 12. This constitutes a double wrench construction so that either one of the head members may be used. In other respects it is similar to the forms previously described.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A wrench, comprising a head member with stationary and adjustable jaws pivotally connected with a handle, means for holding said head member in adjusted angular positions on its pivotal axis, means for securing said holding means in the adjusted positions and means automatically releasing said se-

curing means in the closed position of the jaws.

2. A wrench, comprising a head member with stationary and adjustable jaws pivotally connected with a handle, and means for holding said head member in adjusted angular positions on its pivotal axis, comprising teeth projecting from a tubular member fixed in a lug from said head member, said tubular member engaging in apertures in lugs on said handle, a row of teeth on one of the lugs of said handle and encircling said teeth, and a disc with diametrically opposite teeth engageable simultaneously in the spaces between said teeth.

3. A wrench, comprising a head member with stationary and adjustable jaws pivotally connected with a handle, and means for holding said head member in adjusted angular positions on its pivotal axis, comprising teeth projecting from a tubular member fixed in a lug from said head member, said tubular member engaging in apertures in lugs on said handle, a row of teeth on one of the lugs of said handle and encircling said teeth, and a disc with diametrically opposite teeth engageable simultaneously in the spaces between said teeth, said disc being resiliently urged into the engaged position.

4. A wrench, comprising a head member with stationary and adjustable jaws pivotally connected with a handle, means for holding said head member in adjusted angular positions on its pivotal axis, and means for securing said holding means in the adjusted positions and means automatically releasing said securing means in the closed position of the jaws, comprising a finger pivotally mounted in a recess in said stationary jaw and engaging a flange upon a disc having teeth engaged between other teeth arranged to hold the head member at an angular position with said handle, a spring for urging the finger into the said engaged position, and a pin connected with the stationary jaw so that in closed position of the jaws to engage against said finger and lift the finger off of the flange.

In testimony whereof I have affixed my signature.

FREDERICK SCHWEIGERT.
